(**) Term: **14 Years**

(57) **CLAIM**

(21) Appl. No.: **29/493,657**

The ornamental design for a scalp-treatment apparatus, as shown and described.

(22) Filed: **Jun. 12, 2014**

DESCRIPTION

(51) **LOC (10) Cl.** **24-02**

FIG. 1 is a front view of a first embodiment of a scalp-treatment apparatus;

(52) **U.S. Cl.**

FIG. 2 is a back view thereof;

USPC **D24/133**

FIG. 3 is a right view thereof;

(58) **Field of Classification Search**

USPC D24/133, 134, 138, 144, 188; 604/21;

424/401; 607/139

FIG. 4 is a left thereof;

See application file for complete search history.

FIG. 5 is a top view thereof;

(56) **References Cited**

FIG. 6 is a bottom view thereof;

U.S. PATENT DOCUMENTS

FIG. 7 is a perspective view thereof;
